UNITED STATES PATENT OFFICE.

CHARLES W. HUBBARD, OF WESTON, MASSACHUSETTS.

SPINNING AND WINDING APPARATUS.

1,201,049.

Specification of Letters Patent. Patented Oct. 10, 1916.

Application filed December 4, 1913. Serial No. 804,753.

To all whom it may concern:

Be it known that I, CHARLES W. HUBBARD, a citizen of the United States, residing at Weston, county of Middlesex, State of Massachusetts, have invented an Improvement in Spinning and Winding Apparatus, of which the following description, in connection with the accompanying drawing, is a specification, like characters on the drawing representing like parts.

In my Patents Nos. 795,981 and 795,982 dated August 1, 1905, I have illustrated and described different embodiments of a spinning and winding apparatus which is constructed to lay the yarn or thread in transverse layers across the end of a thread mass. The devices shown in said patents comprise a rotary support for the thread mass on which the thread mass is built up, a winding or thread-laying plate by which the yarn or thread is compactly laid on the end of the thread mass, a yarn guide which gives the yarn or thread a traverse, and means for rotating the yarn support and winding plate at different speeds thereby to cause the winding operation and to reciprocate the yarn guide to give proper traverse to the yarn. The yarn guide in said patented structures is given its reciprocatory movement by means of a cam which is driven by suitable differential gearing.

My present invention aims to provide an improved form of winding apparatus which is designed to overcome some defects which develop in the devices of the patents.

One of the features of my present invention relates to the manner of supporting and operating the yarn guide by means of which the latter will have a freer action.

Another feature relates to an improved device for positively drawing the yarn from its source of supply and delivering it to the winding member, and other features of the invention relate to details of mechanical construction, all as more fully herein-after set forth and then pointed out in the appended claims.

Referring to the drawings wherein I have illustrated my invention: Figure 1 is a sectional view showing a portion of a spinning frame and one of my spinning and winding devices. Fig. 2 is an enlarged vertical sectional view through one form of my spinning and winding device on the line *c-c*, Fig. 5. Fig. 3 is a section on the line *x-x*,

Fig. 2. Fig. 4 is a section on the line *y-y*, Fig. 2. Fig. 5 is a top plan view of Fig. 2. Fig. 6 is a section on the line *a-a* in Fig. 3. Fig. 7 is a view similar to Fig. 2 but showing a different embodiment of the invention, 60 said view being a section on line *f-f*, Fig. 10. Fig. 8 is a section on the line *b-b*, Fig. 7 looking upwardly. Fig. 9 is a section on the line *b-b*, Fig. 7 looking downwardly. Fig. 10 is a plan view of Fig. 7. 65 Fig. 11 is a section on the line *d-d*, Fig. 8. Fig. 12 is a detail of the thread guide shown in Fig. 9. Fig. 13 is an enlarged sectional view through bearing plate at the upper end of the cage. 70

The devices shown in the drawing embody the main features of the devices shown in my aforesaid patents, that is, a rotary thread-supporting member, a winding member, means for rotating the winding and 75 thread-supporting members at different speeds, and a thread guide for giving traverse to the yarn or thread as it is laid on the thread mass. The thread-supporting member is herein shown as in the form of 80 a plate 1, which will preferably be supported in a basket or cage 2, within which the thread or yarn mass 3 is built up and which is herein shown as formed of longitudinal members 96 which are connected by 85 bands or hoops 97. This cage 2 with its thread-supporting member 1 is shown as detachably secured to a hollow spindle 4, having a pinion 5 thereon which meshes with and is driven by a driving gear 6. 90

The winding member includes a winding or thread-laying plate 7 which rests on the upper end of the thread mass 3 and is rotated relative thereto to cause the thread or yarn to be wound or laid on the thread mass. 95 This winding member 7 is driven from a spindle 9 which extends down through the hollow shaft 4 and has a pinion 11 thereon which meshes with and is driven by the gear 12. The gears 6 and 12 have a different 100 number of teeth thereon and the shafts 4 and 9 will, therefore, be rotated at different speeds. This causes a differential movement between the winding plate 7 and the thread mass which causes the yarn or thread to be laid on the thread mass, all as described in said patents. The lower end of the spindle 9 is journaled in a bearing 92 and the upper end of said spindle is journaled in a bearing carried by the cage at 105 110

the upper end thereof, the construction being such as to permit the cage to be removed from the spindle.

In the preferred embodiment of my invention the bearing for the upper end of the spindle is formed in a bearing plate 98 which is detachably secured to the cage and which is provided with a bearing for centering the cage. This bearing plate 98 is shown 5 as having a bayonet joint connection with the top ring 97 of the cage so that by giving the plate a slight turning movement relative to the cage, said plate can be unlocked and removed from the cage. This bearing 10 plate 98 is provided with a spindle 100 which is rotatably mounted in a bearing 93 carried by the framework 94. Said spindle 100 is also capable of being moved longitudinally in the bearing 93 so as to permit the 15 bearing plate 98 to be raised from the cage as will be presently described. This bearing plate is also provided in its under side with a recess 101 in which the upper end of the spindle 9 is received, said recess forming a bearing for said spindle.

The bearing 93 is preferably secured to the frame 94 in such a way as to permit it to be moved out of the way whenever the cage is to be removed from its support, and 20 this can conveniently be done by pivotally connecting said bearing to the frame as shown at 95, thus permitting the bearing to be swung upwardly into the dotted line position. The cage 2 is detachably secured to 25 the hollow shaft 4 by means of a pin-and-slot bayonet joint as shown at 89 so that said cage can be readily removed by merely moving it slightly and lifting it off of the shaft. Whenever the cage is to be removed 30 the bearing plate 98 is first unlocked from the cage and is then raised up in its bearing 93 to clear it from the upper end of the spindle 9 and the bearing 93 may then be swung upwardly into the dotted line position, after 35 which the cage can be disconnected from the hollow shaft 4 and removed from the spindle.

The spindle 9 may be made in one piece 40 or may be made in two sections detachably secured together. The latter construction is that which is shown in Fig. 1, and the joint between the two sections of the spindle is shown as situated within the sleeve 4. Where this construction is provided, the upper portion of the spindle can be removed 45 from the cage and thread mass after the latter has been completely wound before the cage is removed from its support, if desired. Where the spindle is made in two sections, any suitable connection may be employed 50 for detachably uniting the two sections, that herein shown being in the form of a pin-and-slot bayonet joint 88.

The winding head, which includes the 55 winding plate 7 above referred to, com-

prises a central hub or sleeve 13 which telescopes over the spindle 9 and which is connected thereto so as to rotate therewith, while being capable of moving longitudinally thereof. This can conveniently be 60 provided for by making the spindle with a longitudinal groove 14 in which is received a pin or feather 15 extending from the bushing 13. The winding plate 7 is rigid with the sleeve 13 and said sleeve also has 65 secured thereto a head plate 16 which carries the tension and feeding device herein-after described and which also sustains the differential gear for operating the thread guide.

In the embodiment shown in Fig. 2, the head 16 has associated therewith an internal gear 17 which is driven by the cage or basket 2, said gear having a projection 18 extending therefrom which engages one of 70 the arms 96 of the basket 2, so that the rotation of the cage or basket will be transmitted to the gear 17. 19 is another internal gear loosely mounted on the head plate 16 and operated from the gear 17 through differential gearing so that the gear 19 has a 75 slightly greater or slightly less speed than the gear 17 as desired. This gear 19 has connected thereto and operates the cam plate 20 by which the thread guide is given its 80 traverse. The gears 17 and 19 have a different number of teeth and both gears mesh with a gear 21 loosely mounted on a stud 22 carried in the head 16. The head 16 is driven from the spindle 9 while the cage 2 85 will rotate at the same speed as the tubular shaft 4. Since these two shafts 4 and 9 are rotated at different speeds, it follows that the head 16 will have a different speed of rotation from the cage and the thread mass. The co-operation of the gears 17, 19 and 21 causes the cam-operating gear 19 to have a 90 faster or slower speed than the gear 17 dependent upon whether the gear 19 has a less or greater number of teeth than the gear 17. 100

In my prior patents, the yarn guide traveled back and forth in a guideway and received its reciprocatory movement directly from the cam. In the present embodiments of my invention the thread guide is 105 mounted on a swinging member which has a free swinging movement, the operation of which is determined by the cam 20. In Fig. 2, the thread guide is shown at 23 and it is sustained by an arm 24 pivoted to the head plate 16, at 25, said arm being herein shown as provided with a roller 26 which engages the inner periphery of the cam 20. This thread guide travels back and forth in a slot or opening 27 formed in the winding 110 plate 7. The cam 20 acts to swing the arm 24 and thread guide 23 inwardly toward the axis of rotation and a suitable spring device is employed to give the arm its movement in the other direction. In the illustrated em- 115

- bodiment of the invention this spring device is shown as a coiled spring 28 situated in a recess 29 in the plate 16 and acting against a plunger 30 which engages an arm 31 rigid with the stem or arm 24. Any other suitable spring mechanism for accomplishing this purpose might be used, however, without departing from the invention.
- In my former patents the yarn or thread 10 passes from its source of supply directly to the thread guide and the winding plate and as a result the tension which was placed on the yarn was due to the drawing action resulting from the relative movement between the winding plate and the yarn mass. This produced more or less uneven tension on the yarn because of the varying position of the thread guide. In my present invention I have provided means intermediate of 20 the source of supply and the winding plate which acts on the thread or yarn and operates to draw the yarn from its source of supply with an even, steady motion and to deliver the yarn to the thread guide at a uniform speed. I find that by means of this construction the yarn can be laid more evenly and uniformly and with less liability of breakage than with the construction illustrated in my patent. This yarn-drawing device 30 comprises a plurality of positively driven grooved rolls around which the yarn or thread passes and which are somewhat in the nature of capstans, and two positively driven flat faced rolls between which the 35 yarn is fed. This construction is perhaps best seen in Figs. 3, 5 and 6 wherein 31 and 32 are two shafts journaled in the head block 16 and carrying gears 33 and 34 respectively that mesh with a gear 35 which is 40 rigid with the gear 21, it being remembered that the gear 21 is journaled on the shaft 22 carried by the head block 16 but meshes with the internal gear 17 which is driven by the basket or cage 2. The differential movement between the gear 17 and the head block 16 causes the gear 21 to rotate on its axis and the rotation of this gear is transmitted to the gear 35, and from the latter to the gear 33 and 34 and the shafts 31 and 32. The 45 shaft 31 has fast thereon a double grooved pulley 36 and the shaft 32 has fast thereon a pulley 37, both of these pulleys being situated above the head block 16. The shaft 32 also has thereon a roll 38 preferably having 50 a serrated face with which co-operates another roll 39 fast on the shaft 40 journaled in the block 16 and provided at its lower end with a gear 41 that meshes with the internal gear 17. The yarn or thread 8 is led from 55 the source of supply down through the hollow upper end of the spindle 9, and out through an opening in the side of said spindle, thence down through a guide eye 42 sustained by the head 16, thence around one 60 of the pulleys 36, around the pulley 37, thence around the other pulley 36 and between the rolls 38 and 39 and from the latter to an aperture 43 in the block 16 through which it passes to the thread guide 23.
- The rolls 38 and 39 constitute presser rolls 70 which grip the thread or yarn between them and which operate to hold the yarn taut about the pulleys 36, 37. These pulleys 36, 37 act somewhat as capstans and as they are positively driven they operate to draw 75 the yarn or thread 8 from its source of supply and to deliver it to the thread guide 23. By means of this construction the yarn or thread 8 is drawn from its source of supply at a uniform speed and any strain or tension 80 incident to this operation is taken entirely by the rolls 36, 37 and not by the thread guide 23 or the winding plate 7. The thread is thus laid on the thread mass under a constant tension and there is no danger that it 85 will become broken by strain or tension that is put thereon by the winding plate. I will preferably mount the shaft 40 in a swinging member so as to permit the roll 39 to be moved toward and from the roll 38 90 thereby to facilitate the threading up of the machine. As herein shown the shaft 40 is rotatably mounted in a bearing 44 carried by a swinging arm 45 that is mounted on the hub 13 and is adapted to have a swinging 95 movement thereabout.
- 46 is a spring carried by the block 16 and acting against the plunger 47 which in turn has engagement with the arm 16, said spring 46 serving to yieldingly hold the roll 39 in 100 engagement with the roll 38. The roll 39 is shown as provided with the extended hub 48 which provides a hand-hold, by which the member 45 can be moved to separate the roll 39 from the roll 38.
- In the embodiment of the invention shown in Figs. 7 to 12, the thread guide swings in a horizontal plane and the cam for operating the thread guide is inclosed within the winding head. In other respects, 105 however, the construction shown in said Figs. 7 to 12 is substantially like that in Figs. 2 to 6. In Fig. 7 the winding head comprises the central hub 13 and winding plate 7 as above described and also top and bottom plates 50 and 51 between which the gears 17 and 19 are located, the gear 17 having the projection 18 to be engaged by the upright 96 of the cage or basket and the gear 19 having secured thereto the cam 110 20 for operating the thread guide. This cam 20 is shown as located above the lower plate 51 and as sustained by an annular rest 52 carried by the plate. In this embodiment the gear 19 is supported by the cam 115 plate instead of supporting the cam plate as shown in Fig. 2. The differential gearing and the feed device of Figs. 7 to 11 is the same as shown in Figs. 2 to 6. The thread guide in Figs. 7 to 12 is shown at 230 and 120 125 130

it comprises an eye or tubular member carried by an arm 56 which is rigid with a shaft 57 mounted in the bottom plate 51 and the winding plate 7 as shown in Fig. 12. The shaft 57 has rigid therewith an arm 58 carrying a roll 59 which engages the periphery of the cam 20, said roll being held against the cam by the spring 60. The thread guide 230 plays in a slot 61 formed 10 in the winding plate 7 and this slot is slightly curved as seen in dotted lines 9 to conform to the arc of movement of the thread guide 230. 62 designates a guard finger carried by the plate 7, the object of 15 which is to prevent the thread or yarn from being thrown beyond the outer limits of the plate.

Having fully described my invention, what I claim as new and desire to secure 20 by Letters Patent is:

1. In a machine of the class described, the combination with a rotary thread support, of a winding member for winding a thread mass on said support in layers extending transversely of the axis thereof, said winding member resting on the thread mass and means carried by the winding member for positively drawing thread from its source of supply to be delivered to the 30 winding member.

2. In a machine of the class described the combination with a rotary thread support to receive the thread mass as it is wound, of a winding member resting on said mass 35 for winding the thread on said support in layers extending transversely of the axis of the support, said winding member rising as the thread mass is built up, and a combined tension and thread drawing device 40 carried by the member for drawing from its source of supply the thread that is delivered to the winding member.

3. In a machine of the class described, the combination with a rotary thread support, of a winding member for winding a thread mass on said support in layers extending transversely of the axis thereof, said winding member resting on the thread mass and movable axially of the support, 50 and means carried by the winding member and actuated thereby to draw thread positively from its source of supply and deliver it to the winding member.

4. In a machine of the class described, 55 the combination with a rotary thread support, of a winding member for winding a thread mass on said support in layers extending transversely of the axis thereof and a combined tension and thread drawing device carried by the winding member and actuated thereby for drawing thread from its source of supply and delivering it to the winding member.

5. In a machine of the class described, 65 the combination with a rotary thread sup-

port, of a winding member for winding a thread mass on said support in layers extending transversely of the axis thereof, said winding member resting on the thread mass and movable axially of the support, 70 and means carried by the winding member for maintaining a uniform tension on the thread as it is delivered to the winding member.

6. In a machine of the class described, 75 the combination with a rotary thread support, of a winding member for winding a thread mass on said support in layers extending transversely of the axis thereof, said winding member resting on the thread 80 mass and movable axially of the support, and positively driven rolls carried by the winding member for drawing the thread from its source of supply.

7. In a machine of the class described, 85 the combination with a rotary thread support, of a winding member for winding a thread mass on said support in layers extending transversely of the axis thereof, said winding member resting on the thread mass and movable axially of the support, 90 rolls carried by the winding member for drawing the thread from its source of supply and means actuated by the winding member for positively rotating said rolls. 95

8. In a machine of the class described, the combination with a rotary thread support, of a winding member for winding a thread mass on said support in layers extending transversely of the axis thereof, 100 said winding member resting on the thread mass and movable axially of the support, and positively driven tension pulleys and rolls carried by the winding member for drawing the thread from its source of supply 105 and delivering it to said winding member under a uniform tension.

9. In a machine of the class described, the combination with a rotary thread support, of a winding member for winding a 110 thread mass on said support in layers extending transversely of the axis thereof, said winding member resting on the thread mass and movable axially of the support, tension pulleys and rolls carried by the 115 winding member for drawing the thread from its source of supply and delivering it to said winding member under uniform tension and means actuated by the winding member for positively driving said pulleys 120 and rolls.

10. In a machine of the class described, the combination with a rotary thread support, of a winding member for winding a 125 thread mass on said support in transverse layers, means to rotate the winding member, said winding member resting on the thread mass and including a thread guide and differential gearing for actuating the latter and thread drawing means carried 130

- by the winding member and actuated by said differential gearing for drawing thread positively from the source of supply and delivering it to said thread guide.
5. 11. In a machine of the class described, the combination with a rotary thread support, of a winding member for winding a thread mass on said support in transverse layers, means to rotate the winding member, 50
10 said winding member resting on the thread mass and including a thread guide and differential gearing for actuating the latter and thread drawing rolls carried by the winding member and means to actuate 55
15 said rolls positively from the differential gearing.
12. In a device of the class described, the combination with a hollow shaft, of a cage or basket detachably secured to the upper 60
20 end thereof and provided with a thread support, a second shaft extending through said hollow shaft, means to rotate said shafts at different speeds, a spindle forming an extension of the said second shaft and extending 65
25 axially through the cage, a bearing at the upper end of the cage for the upper end of the spindle, means for maintaining the cage properly centered, a winding member in said basket including a winding plate
30 to engage the thread mass, a thread guide and means actuated partly by the cage and partly by the spindle to actuate said thread 70
35 guide.
13. In a device of the class described, the combination with a hollow shaft, of a cage or basket detachably secured to the upper end thereof, a second shaft extending through said hollow shaft and provided with a spindle extension, means to rotate 75
40 said shafts at different speeds, a bearing plate at the upper end of the cage in which the upper end of the spindle extension has a bearing, said plate having associated therewith a bearing for the upper end of the cage, 80
45 and means for laying the thread in the cage in layers extending transversely of the axis of rotation thereof.
14. In a device of the class described, the combination with a cage or basket provided 85
90
- with a thread support, of a spindle extending axially through the cage, means to rotate the cage and spindle at different speeds, a bearing plate sustained by the upper end of the cage and forming a bearing for the upper end of the spindle, said plate having a stud extending therefrom, a bearing in which said stud rotates and by which the cage is held centered and means for laying the thread in the cage in layers extending transversely of the axis of rotation thereof. 60
15. In a device of the class described, the combination with a cage or basket provided with a thread support, of a spindle extending axially through the cage, means to rotate the cage and spindle at different speeds, 65
70 a bearing plate sustained by the upper end of the cage and forming a bearing for the upper end of the spindle, said plate having a stud extending therefrom and a bearing in which said stud rotates and by which the cage is held centered, said hollow plate being removably sustained by the cage and movable axially through the bearing.
16. In a device of the class described, the combination with a rotary shaft, of a cage or basket detachably secured to the upper end thereof, a spindle extending axially through the cage, means to rotate the cage and spindle at different speeds, a bearing plate detachably secured to the upper end 75
80 of the cage and forming a bearing for the upper end of the spindle, said bearing plate having a journaled stud extending therefrom, a bearing in which said stud is rotatably mounted and through which said stud can move axially whereby when the bearing plate is disconnected from the cage and moved axially thereof, said plate is withdrawn from the spindle thus permitting the cage to be removed. 90

In testimony whereof, I have signed my name to this specification, in the presence of two subscribing witnesses.

CHARLES W. HUBBARD.
